UNITED STATES PATENT OFFICE

HENRY C. GILLESPIE, OF HUNTINGTON, WEST VIRGINIA, ASSIGNOR TO ARDCO MANUFACTURING COMPANY, OF HOBOKEN, NEW JERSEY, A CORPORATION OF NEW JERSEY

AUTOMATIC RAIL LUBRICATOR

Application filed October 4, 1929. Serial No. 397,324.

The present invention relates to lubricating devices, and has particular reference to a mechanism for automatically feeding grease or other lubricant to the inner side of the outer rail on the curve of a railroad track.

An object of the present invention is to provide a lubricator of this type which may be readily mounted between adjacent ties of a track so that the device may be located at the desired point in advance of the curve and requires no special construction of rail, tie or other part of the track.

Another object is to provide a lubricator which positively ejects or feeds predetermined quantities of a lubricant to the desired point on the rail and which does not vary in quantity of feeding with the variations in the viscosity of the lubricant so that a semi-fluid lubricant will be fed in the same proportionate amount as will a heavy grease lubricant.

The invention further aims at the provision of a lubricator embodying the above characteristics and which is provided with an actuating lever so mounted on the lubricator as to lie in the path of a wheel flange so that the lever may be reciprocated by the wheel flange, and having a peculiar mounting to intermittently and positively eject the lubricant from the device onto the rail.

A still further object of the invention is to provide an intermittent actuator which is detachably connected to the body portion of the device so that the actuator may be easily adjusted for operation, may be interchanged when worn out or broken without discarding the entire device, and which also admits of the operation of the entire device even though the actuator may be out of line with the main or feed shaft of the lubricator.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a perspective view of a portion of a railroad track showing a lubricator con-

structed according to the present invention applied thereto.

Figure 2 is a horizontal section taken through the track substantially on the line 2-2 of Figure 1, the section being taken longitudinally through the lubricator.

Figure 3 is a transverse section taken through the actuating device of the lubricator on the line 3-3 of Figure 2 and showing the adjacent portion of the track, and

Figure 4 is a similar view taken on the line 4-4 of Figure 2, the dotted lines showing a wheel engaging the actuating lever.

Referring to the drawings, 10 and 11 designate the opposite rails of a railroad track which are supported upon ties 12 and 13.

The lubricator comprises a receptacle 14 of suitable size to fit between the ties 12 and 13 and which is provided near its upper end with straps or brackets 15 which project from opposite sides of the receptacle 14 to engage across the opposite ties 12 and 13 for supporting the receptacle 14 and holding it rigidly in position. The straps 15 are secured to the ties 12 and 13 by nails, screws or the like as shown.

The receptacle 14 is constructed with its opposite sides converging downwardly to a rounded bottom 16, as shown in Figure 4, and is adapted to contain grease or other suitable lubricant which gravitates to the bottom 16 where it may be suitably collected and fed out to one of the rails. The rounded bottom 16 of the receptacle forms the lower part of a worm conveyor casing 17, the casing being cylindrical and extending lengthwise through the bottom portion of the receptacle as shown in Figure 2. The casing 17 is provided, within the receptacle 14, with an opening or cut away portion 18 which may be of less length than that of the receptacle 14 and through which the grease or other lubricant flows into the worm conveyor housing 17.

The receptacle 14 is provided with a cover 19 for housing in the grease or lubricant and protecting it against rain, dirt and the like.

The conveyor housing 17 is provided with a worm conveyor or feed screw 20 which extends preferably throughout the length of the housing 17 and which is mounted on a shaft

21 at its inner end, the shaft projecting through a bearing 22 carried upon the inner end of the receptacle 14 and providing an abutment against which the inner end of the conveyor 20 seats so as to hold the conveyor 20 against longitudinal displacement under pressure of the lubricant being fed.

Of course the conveyor 20 may be mounted in any other suitable way found expedient to manufacture and use.

The outer end of the conveyor housing 17 carries a reducer connection 23 to the outer end of which is connected a nozzle 24, the latter being curved or given any other suitable shape for disposing the outlet end 25 of the nozzle at the desired point of delivery of the lubricant. In Figures 1 and 2, the nozzle 24 is shown as being curved substantially with its open end 25 lying against the inner side 20 of the rail 11.

The means employed for operating the worm conveyor 20 comprise a shaft 26 mounted in a bearing bracket 27 having a strap portion which extends between the ties 12 and 13 and is secured thereto for holding the shaft 26 substantially in line with the shaft 21. The shaft 26 is connected to the shaft 21 preferably by a detachable flexible coupling 28 which may be in the form of rubber hose or the like secured to the shafts 21 and 26 by cotter pins or other readily removable devices.

The outer end of the shaft 26 has keyed or otherwise fixed thereto a ratchet wheel 29, and the shaft 26 pivotally carries outwardly of the ratchet wheel 29 a lever 30 which has a long arm adapted to extend upwardly at an inclination and which has its upper end bent at a suitable angle to provide a trip 31 which is adapted to lie in the path of the flange 32 of a wheel 33, as shown in dotted lines in Figure 4. The lever 30 is provided upon its lower end with a laterally extending weight portion 34 for normally urging the trip 31 into raised position and in the path of the wheel flange 32. Any suitable means may be provided for limiting the swing of the lever 30 under action of the weight 34, in the present instance the road bed 35 being built up beneath the weight 34 to support it and hold the lever 30 in desired normal position.

The lever 30 is provided near its pivotal support with a pawl 36 mounted on a pin 37 and having a weighted inner end or heel 38 normally holding the pawl 36 in engagement with the ratchet wheel 29. The teeth of the ratchet wheel 29 and the location of the pawl 36 being such as to advance the ratchet wheel 29 in one direction as the trip 31 is depressed.

In operation, a wheel passing over the rail 10, adjacent the inner side of which the lever 30 is mounted, engages the trip 31, depresses the same and swings the lever 30 with the pawl 36 downwardly in one direction so as to turn the ratchet wheel 29 therewith and

rotate the shaft 26. As soon as the wheel passes over the trip 31 the weight 34 returns the lever 30 to normal position as shown in Figure 3.

The turning of the shaft 26 is transmitted through the flexible coupling 28 to the shaft 21 of the lubricator, and the worm conveyor or screw 20 is turned. The helix of the conveyor 20 is disposed in such direction as to feed outwardly toward the rail 11 and the grease or other lubricant settling downwardly in the receptacle 14 passes through the opening 18 into the spaces between the convolutions of the helix. The conveyor or feed screw 20 is of uniform pitch throughout so that there will always be a predetermined definite quantity of lubricant advanced by the conveyor 20 irrespective of the nature of the lubricant or of the condition of the same.

The lubricant is ejected forwardly into the reducer 23 where the rate of feed is accelerated so that the lubricant is ejected through the nozzle 24 with sufficient force to project the grease or other lubricant upon the surface of the rail 11 in position to be taken up and spread by the flanges of the wheels passing over the rail.

It is apparent that by the settling and warping of the ties the shafts 21 and 26 will be thrown out of line and also that the bracket 27 will shift and settle incident to the strain placed upon it by impact of wheels with the trip 31. The flexible coupling 28 admits of these relative movements and at the same time transmits the action of the lever 30 to the lubricant mechanism. When the trip 30 together with ratchet wheel 39 and pawl 36 becomes worn or broken, the shaft 26 may be uncoupled from the coupling 28 and the entire actuator discarded by removal of the bracket 27. A new actuator may be quickly substituted and connected to the coupling 28. The plate 19 may be easily removed for inspection of the contents of the receptacle 14 and for refilling the same at definite intervals.

It is obvious that various changes and modifications may be made in the details of construction and design of the above specifically described embodiment of this invention without departing from the spirit thereof, such changes and modifications being restricted only by the scope of the following claims.

What is claimed is:

1. An automatic track lubricator comprising a receptacle, means for suspending the receptacle between adjacent ties of a track, a screw conveyor mounted in the bottom of the receptacle and extending from one end thereof toward one rail of the track, a housing for the conveyor, said receptacle having converging side walls merging into said housing for directing grease downwardly into the

conveyor, a nozzle connected to the outer end of the housing and extending to one rail of the track, a main shaft connected to the inner end of the conveyor, a second shaft, means for supporting the second shaft substantially in line with the main shaft, means flexibly connecting said shafts together, a ratchet wheel on the outer end of the second shaft, a lever pivotally mounted on the second shaft
5 adjacent the ratchet wheel, a weighted pawl carried by the lever and normally urged into engagement with the ratchet wheel, said lever having a long arm with a trip at its outer end arranged to lie closely adjacent the inner
10 side of a rail of the track, said lever having upon its other end an extension for normally maintaining the trip in raised position.
15

2. An automatic track lubricator comprising a receptacle mounted between adjacent ties of a track, a conveyor mounted in the receptacle and extending therefrom, a housing for the conveyor, a nozzle connected to the housing and extending to one rail of the track, a shaft connected to the conveyor, a
20 second shaft supported substantially in line with said first shaft, flexible connecting means between the shafts, a ratchet wheel on the outer end of the second shaft, a lever pivotally mounted on the second shaft, a
25 weighted pawl carried by the lever and normally urged into engagement with the ratchet wheel, said lever having an arm with a trip at its outer end arranged to lie closely adjacent the inner side of a rail of a track, said
30 lever having means for normally maintaining the trip in raised position.
35

In testimony whereof I affix my signature.
HENRY C. GILLESPIE.
